UNITED STATES PATENT OFFICE

FRANK WOLF, OF NEW YORK, N. Y.

HOLDER FOR CONTAINERS OR STORAGE VESSELS

Application filed December 24, 1928. Serial No. 328,106.

This invention relates to improvements in holders for containers or storage vessels; especially tubes of soft metal or some other substance which can be squeezed to expel the contents.

An object of the invention is to provide a holder or stand for a collapsible tube designed to engage the stand firmly and hold it in upright position, while leaving the stand

10 exposed so that it can be easily handled. For this purpose I shape the stand so that it has suitable portions for pressing against the outside of the tube, preferably close to the top, so that the tube will be firmly supported

15 and can not slip out of place.

Collapsible tubes are usually provided with a conical top, the outer edge of which projects somewhat to form a peripheral bead or flange. Below this bead-flange the sides of the tube

20 are more or less soft and afford very convenient points of engagement for the holder when the tube is disposed therein. In the practice of my invention I seek to utilize this condition by providing a holder comprising

25 upright members which bear the weight of the tube and so carry the portions for pressing against the tube and thus securing it in position. The legs or upright members of the stand or holder are held together at the top by a member which encircles the upper part of the tube and means are provided for retaining the legs in gripping position.

30 A further object of this invention is to provide a stand which will indent the outside of the tube when it engages the tube, and thus afford a very positive grip to prevent displacement of the tube.

35 Other objects and advantages of the invention will appear from the following description, taken with the accompanying drawings in which several embodiments of the invention are illustrated. I of course do not want to be limited to the exact construction shown but reserve the right to make changes in details, not necessarily presented herein but nevertheless embraced within the scope of the invention.

40 On the drawings,

45 Figure 1 shows a side view of a stand or

holder for a tube according to one form of my invention;

Figure 2 is a view seen from the right of Figure 1;

Figure 3 shows in side view a modification;

Figure 4 illustrates a detail;

Figure 5 is a side view of another modification;

Figure 6 is a side view of a further modification of the invention; and

Figure 7 is a view seen from the right of Figure 6.

On the drawings the same numerals identify the same parts throughout.

In Figures 1 and 2, the collapsible tube is shown at 1, and it has at its upper end the conical top 2 terminating in the usual threaded outlet neck 3 which is ordinarily closed by a screw cap. Over the conical top 2 is fitted a member 4 which has the form of a cover and is likewise conical, the neck 3 projecting out of the upper extremity of this cover. Attached to the cover are the upper ends of the legs 5 and 6, the opposite ends 7 being wide to serve as feet, so that the holder can be stood in upright position upon a shelf or other support. Each of the legs may have projections 8 on its inner edge so that, when the legs are in position to hold the tube 1 the projections 8 make indentations 9 in the sides of this tube just below the bead-flange 10, around the periphery of the top 2.

I have shown in Figure 1 the stand as made up of one leg 5, which is fixed to the cover 4 and the other leg 6 hinged to the cover at 6a. To put the holder in place the hinged leg 6 is simply swung outward, and the upper end of the tube passed through the cover 4 from below, one side of the tube being forced against the projection 8 on the fixed leg 5. The other leg 6 is then moved toward the tube to make the projection 8 thereon grip the tube at a point opposite the projection on the leg 5. To hold the hinged leg in place I provide it with a pair of lateral curved arms 11 affixed to the top of the hinged leg at the hinge 6a and the cover 4 has elastic fingers or projections 12 extending downward, with their ends turned out. Thus when the hinged leg 6 is

moved toward the tube, the ends of the arms 11 pass under the projections 12 and press firmly against the sides of the tube along the flange 10. The tube is thus gripped securely; and at the same time the hinged leg 6 is held in supporting position. If desired, the projection 8 may be omitted from the hinged leg 6 and the arms 11 in cooperating with the projections 12 may be relied upon to indent the adjacent sides of the tube 1.

10 In Figure 3 the member 4a is shown as a flat conical ring instead of a cover, but otherwise the construction is the same as described above.

15 The arms 11 and projections 12 can be omitted and a different form of retaining means employed for the legs 5 and 6, as shown for example in Figure 5, whereon 13 is an encircling ring which need only be lifted to permit the hinged leg to move outward. This ring may 20 have a sliding bearing 14 encircling the leg 5 so that it cannot be detached. On the other leg may be a bearing 14a, sliding or fixed, with a catch 14b. The legs diverge from the top 25 and when the ring 13 slides down to engage the catch 14b, it draws the legs towards each other; and releases the legs when it is pushed up. Near the lower end the legs may have 30 apertures or recesses therein indicated at 15 for the ends of the bottom 16 of the tube.

35 In Figures 6 and 7, one or both legs 17 and 18 may be hinged at their lower ends 19 to a base 20. The legs have arms 11, as above described, and the member 4a is provided with the elastic fingers 12 to operate as before. The legs 17 and 18 may also have the 40 projections 8 on their inner sides as before to indent the tube 1.

I may obviously make the holder of Figures 45 1, 2, 3 and 5 with both legs hinged to the member 4 or 4a, with any kind of retaining means to hold the legs in engaging position, as above set forth.

To enable the stand to serve for tubes of different lengths, the legs may be made of two 50 sections, a lower 21 and an upper 22, with the former carrying a bearing sleeve 23 to receive the lower end of the upper section 22. This sleeve has a slot 24, and each section 22 has a pin 25 to keep it from being pulled out of the sleeve 23. Thus the stand can be adjusted. The recesses 15 may be in the section 21.

The member 4 or 4a serves to strengthen 55 and protect the top 2 when the tube is put into the holder, and afterwards squeezed, and the stand or holder enables the tube to be more easily handled in use, and put away when not needed.

60 I claim:

1. A holder stand for a collapsible tube with a soft body and a rigid top having a stiff bead-flange at its periphery, said stand comprising a cover and legs for supporting the same, said cover being of a shape to pro-

vide a seat therein for receiving the top of the tube, and means at the upper ends of the legs adapted, upon the insertion of the top in its seat, to engage the soft body below the bead-flange and lap under the bead-flange so as to retain the top in its seat and hold it to the cover for the support of the tube by its top and in a pendant position. 70

2. A holder stand for a collapsible tube with a soft body and a rigid top having a 75 stiff bead-flange at its periphery, said stand comprising a cover and legs for supporting the same, said cover being of a shape to provide a seat therein for receiving the top of the tube, means at the upper ends of the legs 80 adapted, upon the insertion of the top in its seat, to engage the soft body below the bead-flange and lap under the bead-flange so as to retain the top in its seat and hold it to the cover for the support of the tube by its top and in a pendant position, and extensions 85 provided by the legs adapted to afford and maintain an engagement with the pendant tube. 90

3. A holder stand for a collapsible tube 95 having a soft body and a rigid top with a bead-flange at its periphery, the stand comprising relatively movable legs, a member to be fitted upon the top of said tube and holding the upper ends of the legs when the stand is in position, and projections on one or more of said legs at the inner side thereof to indent and press into the outside of the tube at said flange, when the stand is in position, and support the tube. 100

4. A holder stand for a collapsible tube having a soft body and a rigid top with a peripheral bead-flange, the stand comprising 105 a pair of legs, a member to fit upon the top, the legs being attached to said member, projections on the inner sides of said legs, to indent the top at the flange to secure the tube in the stand, and means comprising lateral arms on one leg and elastic fingers on said member to press the arms against the tube 110 just below said flange. 115

5. The holder indicated according to claim 3 wherein the member has the form of a flat ring fitting upon the top around its periphery. 120

6. A holder stand for a collapsible tube with a soft body and a rigid top surrounded by a bead-flange, the stand comprising legs, 125 a cover member on the top to which the legs are attached at their upper ends, one leg being hinged to said member, projections on the inner sides of said legs to indent the outer surface of the tube below the top at said flange, said member having downward extending spring fingers to project across said flange, and an arm on said hinged leg to pass under said fingers and grip the tube beneath the flange and close to said top, when the leg is 130 swung toward the tube; so that the leg is

held in position relative to the other leg to enable the stand to carry the tube.

7. A holder stand for a collapsible tube with a soft body and a rigid top having a bead-flange at its periphery, the stand comprising legs, a cover member for said top, the legs being attached to said member, one leg being hinged thereto for movement relatively to the other leg, and projections on the inner 10 sides of the legs, said projections being adapted on the movement of the hinged leg toward the other leg, to indent and press into said tube just below said flange.

8. A holder stand for a collapsible tube 15 having a soft body and a rigid top, the stand comprising legs, one of which is movable relatively to the other, a member shaped to fit on the top of the tube for maintaining the legs in a fixed relation when the stand is in 20 position, means projecting inwardly from at least one of said legs to press against and into the side of the tube for the support of the tube within the holder, said legs comprising upper and lower sections extensibly 25 connected to suit the length of the tube, said lower sections having openings for receiving therein extremities of the lower portions of the tube.

In testimony that I claim the foregoing as 30 my invention, I have signed my name hereto.

FRANK WOLF.
